Attorney

UNITED STATES PATENT OFFICE

WILLIAM MURRAY, OF ASTORIA, LONG ISLAND, NEW YORK

MITER-CUT FINDER

Application filed January 21, 1929. Serial No. 333,850.

This invention relates to new and useful improvements in miter cut finders or what are frequently known as miter or bevelled gauges. The primary object of this invention resides in the provision of an instrument of this character that includes generally a main stock or handle having pivotally associated with one end thereof a pair of swinging arms or blades, the said blades being operatively associated so as to operate in unison, said association consisting of intermeshing gears which gears are protected by housings formed within the main stock or handle.

Further, an object of the invention is to construct said stock or handle from a pair of sections, each of which is so formed as to provide a stock or handle capable of entirely receiving the swinging blades when the gauge is not in use in order that it may be conveniently carried in the pocket, and without presenting to the pocket any rough edges or protruding points.

Furthermore, the structure of the gauge is such as to enable it to be entirely disassembled for cleaning, repair or renewal purposes.

With the foregoing and other objects in view as the nature of the invention will be better understood from the following specification and accompanying drawing, wherein:

Figure 1 is a plan view of my improved miter cut finder, the swinging blades or arms shown in full and dotted line positions.

Figure 2 is a fragmentary longitudinal transverse section through the gauge, the said blades or arms being in entirely closed position.

Figure 3 is an inner face perspective of one of the sections of the main stock or handle, and

Figures 4, 5 and 6 are detailed sections taken substantially upon the lines 4—4, 5—5 and 6—6 of Figure 2.

Now, having particular reference to the drawing, my miter cut finder consists of the three general units of a gauge of this character, that is, the main stock or handle A and the pair of swinging blades or arms B—B. The said stock or handle is of predetermined length, width and thickness, and in this in-

stance, is composed of a pair of mating sections 5—5. The opposed faces of these sections at opposite edges of the stock or handle are formed with blade receiving channels 6—6 that extend to the upper end of the sections and that terminate in spaced relation with the lower ends of the sections as clearly illustrated in Figures 2 and 3. The lower end of each channel is tapered downwardly from the inner edge of the channel as at 7 to accommodate the bevelled free ends of the blades B—B when said blades are swung into the channels. Beneath the lower ends of these blade channels, the said sections are provided with registering set screw openings 8, certain ones of each section being threaded, while those opposed to the threaded ones are counter-sunk at their outer ends, so that set screws 9 may be provided to rigidly interconnect the sections of the stock or handle.

The upper end of each section 5 is formed at its inner face and directly adjacent its respective channel 6 with a rounded gear pocket 10 that opens into the said channel, as clearly illustrated in Figure 3. The stock attached end of each blade B is rounded. Fixed to the inner faces of these blades by welding or the like, and freely rotatable within their respective gear pockets 10 are small gears 11—11, the same having intermeshing engagement with each other as clearly disclosed in Figures 2 and 4. These gears are formed centrally with openings that register with openings in the blades to facilitate the pivotal arrangement of the blades within the stock or handle by suitable pivot pins 12—12. One end of these pins projects slightly beyond the stock or handle and is equipped with a suitable rounded head 13 to facilitate the swinging of its associated blade as well as the rotation of the gear carried by said blade, and obviously by reason of the intermeshing gears a turning of the head in opposite directions will bring about the simultaneous inward or outward swinging of the blades.

As disclosed by the full and dotted line positions of the blades as in Figure 1, it will be understood that the blades may be swung to any required angle.

In view of the foregoing description when considered in conjunction with the accompanying drawing, it will be apparent that I have provided a novel, simple and useful 5 miter cut finder wherein the pivoted ends of the blades are interconnected by a pair of gears, which gears are entirely enclosed within the main stock or handle, so that they will be protected from dirt, dust or other 10 matter that would prevent the proper swinging of the blades into or out of the stock channels.

Even though I have herein shown and described the invention as consisting of certain detailed structural elements, it is nevertheless to be understood that some changes 15 may be made therein without affecting the spirit and scope of the appended claims.

Having thus described my invention, what 20 I claim as new and desire to secure by Letters Patent, is:

1. In a miter cut finder, a stock or handle consisting of a pair of mating half sections in face to face engagement, each 25 section being provided at its inner face with a longitudinal blade receiving channel, the channels of the sections being at opposite longitudinal edges of the stock, each section being further formed at its inner face and at 30 one end of its respective channel with a gear pocket open to the channel only, two blades pivoted to said stock, a gear attached at one end of one blade, a second gear attached to the adjacent end of the other blade 35 and meshing with said first gear, substantially as and for the purpose specified.

2. In a miter cut finder, a stock or handle consisting of a pair of mating half sections in face to face engagement, each section being provided at its inner face with a 40 longitudinal blade receiving channel, the channels of the sections being at opposite longitudinal edges of the stock, each section being further formed at its inner face and at 45 one end of its respective channel with a gear pocket open to the channel only, two blades pivoted to said stock, a gear attached at one end of one blade, a second gear attached at the adjacent end of the other blade 50 and meshing with the first gear, and manipulative means associated with one of the blades whereby to cause the simultaneous rotation of the meshing gears and the swinging of the blades.

55 In testimony whereof I affix my signature.
WILLIAM MURRAY.
